UNITED STATES PATENT OFFICE.

WALDEMAR STENDER, OF BERLIN-CHARLOTTENBURG, GERMANY, ASSIGNOR TO SIE-MENS-SCHUCKERTWERKE GESELLSCHAFT MIT BESCHRANKTER HAFTUNG, OF SIEMENSSTADT, NEAR BERLIN, A CORPORATION OF GERMANY.

FEEDING OF STEAM-BOILER PLANTS.

Application filed September 16, 1924, Serial No. 737,999½, and in Germany September 22, 1923.

My invention relates to improvements in the feeding of steam boiler plants.

When steam boilers are fed in such a manner that the water is first heated in an economizer or waste gas feed heater and then by surplus live steam, two hot water storage receptacles or vessels are required, one behind the economizer and the other behind the steam heater. This is necessary because the water must be passed approximately uniformly through the economizer but through the steam heater to the extent only to which steam is available, while the boiler must again be fed approximately uniformly. A larger quantity of water is furthermore necessary to condense the same quantity of steam than required if the water had not been heated in an economizer because more steam can naturally be condensed with cold water than with hot water. Consequently the storage receptacle for the water preheated by steam must be also made larger when heating the water in an economizer than without such a heater.

To obviate these disadvantages the system of feeding boiler plants according to my invention provides that a portion of the feed water is heated in an economizer while another portion is heated by steam.

In the drawings affixed to this specification and forming part thereof a number of embodiments of my invention are illustrated by way of example.

In these drawings:—

Fig. 1, shows a diagram of the improved feed system and

Figs. 2 and 3 show diagrams of slightly modified systems. Similar reference characters indicate similar parts throughout all the figures of the drawings.

Referring to Fig. 1, 1 is a steam boiler the feed water 3 of which is raised by the pumps 11 and 21. The pump 11 forces the feed water through the economizer 12 into the boiler 1 and the pump 21 drives the feed water through the steam heater 22 into the hot water storage receptacle 23 whence the pump 24 also raises it into the boiler 1.

If little steam is used at the place of con-

22. Simultaneously the output of pump 21 55 can be regulated in dependence from the steam pressure in the pipe 5, likewise by pressure responsive element 40 thru control rod 42 actuating a control valve 43, so that the water in the steam heater 22 is always 60 brought to the same temperature since to a certain quantity of water the corresponding quantity of steam is always added. The storage receptacle 23 is thus charged irregularly but emptied regularly by the pump 24, 65 the water being forced into the boiler 1 in a uniform stream.

In the improved system or arrangement according to my invention not the total quantity of water flows through the economizer but a smaller quantity. The water therefore flows slower and becomes more highly heated: The quantity passing must be so regulated that the water is not heated beyond the boiling temperature prevailing 75 in the boiler. This control is very simple in my improved system since the battery of boilers is quite uniformly fired and the pump 11 delivers uniformly. For greater safety the output of pump 11 may also be 80 regulated in dependence from the temperature of the feed water behind the economizer 12 either by hand or by a thermo-regulator. For regulating the total quantity of the water to be fed into the boiler 85 the pump 24 can be controlled from a water level regulator in known manner. These means will be referred to hereinafter with reference to Fig. 2.

By the system according to my invention 90 not only the storage receptacle behind the economizer is rendered superfluous but the further advantage is obtained that the storage receptacle or reservoir 23 and the pump 24 can be made smaller than if they had to 95 deliver the water already preheated by the economizer because for the condensation of the same quantity of steam less cold water is required than already preheated water, as will be readily understood.

The savings which can be effected by the heating of the feed water are naturally greater the higher are the temperatures attained thereby and the tendency will be to raise the heating as near as possible to the 100 boiling point of the boiler water.

Frequently it happens, however, that the economizer is not able to sustain the boiler

pressure, for instance in the event that it is desired to utilize as waste gas heater for a high pressure boiler plant an old low pressure boiler alone or in conjunction with a waste gas heater or economizer already installed for this low pressure boiler. According to my invention it is possible to arrange in such a case means which bring the water, heated in the economizer system to the pressure of the water in the high pressure boiler, or to arrange between such an economizer system and the water heated by steam a supply means which bring water heated in the economizer to the pressure of the water heated by steam. Provisions may also be made that the hot water or the surplus of hot water produced in the economizer is conducted to the storage receptacle for the water heated by steam.

20 Embodiments of this part of the invention are shown in Figs. 2 and 3.

Referring to Fig. 2, 10 is a low pressure steam boiler serving as additional economizer to which the feed water 3 is supplied by the pump 11 by way of the economizer 12. The high pressure boiler 1 whose steam is conducted to the consumer 4 by the pipe 5 is fed by the pump 31 partly with hot water from the low pressure boiler 10 and partly with water from the hot water storage vessel 23. The hot water storage vessel 23 is charged with water which is supplied to it by the pump 21 by way of the steam heater 22. The steam passing to the heater 22 is controlled by the valve 6 operated, as in Fig. 1, by the pressure responsive means 40 through rod 41 in dependence from the steam pressure in the main pipe 5.

40 The output of pump 31 is regulated in dependence from the water level in the high pressure boiler 1 in any conventional manner, for instance by a float 44, disposed in boiler 1 and acting thru control rod 45 upon a valve 46. The output of pump 11 is regulated in dependence from the temperature behind the low pressure boiler 10 and the pump 21 in dependence from the temperature behind the steam heater 22. For these purposes a temperature responsive control 45 element, of any suitable construction known in the art, is located at the delivery side of low pressure boiler 10, which element through operating gear 48 actuates valve 49, affecting the output of pump 11; similarly 50 a temperature responsive element 50 is provided at the delivery side of steam heater 22 and controls through valve 52 the output of pump 21. All of these different control elements are here indicated merely in diagrammatic and conventional manner, regardless 55 of their detail construction, which is immaterial for the principle involved in the present invention.

During the ordinary service the pump 11 60 does not supply a sufficient quantity of water

to the pump 31 so that the pump 31 takes the missing quantity from the hot water storage receptacle 23 through the pipe 13. If the firing of the boiler 1 is suddenly decreased because the high steam consumption ceases, the evaporation in the boiler drops considerably and consequently also the output of the pump 31 which is controlled by float 44, while the temperature of the water issuing from the economizer may still remain almost unchanged so that there is no reason for a change in the output of the pump 11 which as stated before depends upon the temperature on the delivery side of boiler 10. It may happen as a consequence that the pump 11 supplies more water than the pump 31 requires. The excess of water then flows to the storage vessel 23 through the pipe 13.

Referring to Fig. 3, it will be observed that the water heated in the low pressure boiler 10 is brought to the pressure of the water heated with steam by the pump 31 the water being fed into the hot water storage vessel 23 by said pump. The pump 31 can be regulated in a similar manner as the pump 11 namely in accordance with the temperature behind low pressure boiler 10 (not shown). A pump 41 then feeds the high pressure boiler 1 from the hot water storage receptacle 23 in dependence from the water level in the boiler 1.

What I claim as my invention and desire to secure by Letters Patent is:—

1. A feed system for boiler plants comprising a waste gas heater adapted to heat one portion of the feed water and a live steam heater adapted to heat the other portion of the feed water, means for controlling the quantity of the live steam entering said steam heater in dependence from the steam pressure in the mains and means for controlling the quantity of water flowing through said steam heater in dependence from the quantity of the steam available for its heating.

2. A feed system for boiler plants comprising a waste gas heater adapted to heat one portion of the feed water and a live steam heater adapted to heat the other portion of the feed water, and means for controlling the quantity of the water flowing through the waste gas heater in dependence from the temperature of the water behind said heater.

3. A feed system for boiler plants comprising a waste gas heater adapted to heat one portion of the feed water and a live steam heater adapted to heat the other portion of the feed water, means for controlling the quantity of the live steam entering said steam heater in dependence from the steam pressure in the mains and means for controlling the quantity of the water flowing through the waste gas heater in dependence from the temperature of the water behind said heater.

pendence from the temperature of said water behind said heater.

4. A feed system for boiler plants comprising a waste gas heater adapted to heat

5 one portion of the feed water and a live steam heater adapted to heat the other portion of the feed water, means for controlling the quantity of the water flowing through said steam heater in dependence 50
10 from the quantity of the steam available for its heating and means for controlling the quantity of water flowing through the waste gas heater in dependence from the temperature of the water behind said heater.

15 5. A feed system for boiler plants comprising a waste gas heater adapted to heat one portion of the feed water and a live steam heater adapted to heat the other portion of the feed water, means for controlling 60

20 the quantity of the live steam entering said steam heater in dependence from the steam pressure in the mains, means for controlling the quantity of water flowing through said steam heater in dependence 65
25 from the quantity of the steam available for its heating and means for controlling the quantity of the water flowing through the waste gas heater in dependence from the temperature of the water behind said heater.

30 6. A feed system for boiler plants comprising a waste gas heater adapted to heat one portion of the feed water and a live steam heater adapted to heat the other portion of the feed water, a connection between 70

35 the discharge sides of both water heaters and a pump in said connection for raising the pressure of the water heated in the waste gas heater to pressure of the water heated in the live steam heater.

40 7. A feed system for boiler plants comprising a waste gas heater for heating substantially continually one portion of the feed water and a steam heater for heating intermittently the other portion of the feed 80

45 water, means for feeding both portions to the boiler, means for controlling the quantity of

steam entering said steam heater and means for controlling the quantity of water flowing through said steam heater and means for regulating both of said controls in dependence of the quantity of steam available 50

8. A feed system for boiler plants comprising a waste gas heater for heating substantially continually one portion of the feed water and a steam heater for heating intermittently the other portion of the feed water, means for feeding both portions to the boiler, means for controlling the quantity of steam entering said steam heater and 60
65 means for controlling the quantity of water flowing through said steam heater and means for regulating both of said controls in dependence of the quantity of steam available for heating purposes and a storage vessel 65

for the water heated by steam.

9. A feed system for boiler plants, comprising a waste gas heater for heating substantially continually one portion of the feed water and a steam heater for heating 70
75 intermittently the other portion of the feed water, means for feeding both portions to the boiler, means for controlling the quantity of feed water flowing through said steam heater, and means for actuating said quantity control means in accordance with the amount of steam available for heating.

10. A feed system for boiler plants, comprising a waste gas heater for heating substantially continually one portion of the feed water and a steam heater for heating 80
85 intermittently the other portion of the feed water, means for feeding both portions to the boiler, means for controlling the quantity of feed water flowing through said steam heater, and means for regulating the steam supply to said steam heater in accordance with the amount of steam available for heating.

In testimony whereof I affix my signature.

WALDEMAR STENDER.
